CLAIM

The ornamental design for a body of an electronic vaping device, as shown and described.

DESCRIPTION

FIG. 1 is a front perspective view of a first embodiment of a body of an electronic vaping device;
FIG. 2 is a rear perspective view of the first embodiment of the body of FIG. 1;
FIG. 3 is a front elevation view of the first embodiment of the body of FIG. 1;
FIG. 4 is a rear elevation view of the first embodiment of the body of FIG. 1;
FIG. 5 is a left side elevation view of the first embodiment of the body of FIG. 1;
FIG. 6 is a right side elevation view of the first embodiment of the body of FIG. 1;
FIG. 7 is a top plan view of the first embodiment of the body of FIG. 1;
FIG. 8 is a bottom plan view of the first embodiment of the body of FIG. 1;
FIG. 9 is a front perspective view of a second embodiment of a body of an electronic vaping device;
FIG. 10 is a rear perspective view of the second embodiment of the body of FIG. 9;
FIG. 11 is a front elevation view of the second embodiment of the body of FIG. 9;
FIG. 12 is a rear elevation view of the second embodiment of the body of FIG. 9;
FIG. 13 is a left side elevation view of the second embodiment of the body of FIG. 9;
FIG. 14 is a right side elevation view of the second embodiment of the body of FIG. 9;
FIG. 15 is a top plan view of the second embodiment of the body of FIG. 9;

FIG. 16 is a bottom plan view of the second embodiment of the body of FIG. 9;
FIG. 17 is a front perspective view of a third embodiment of a body of an electronic vaping device;
FIG. 18 is a rear perspective view of the third embodiment of the body of FIG. 17;
FIG. 19 is a front elevation view of the third embodiment of the body of FIG. 17;
FIG. 20 is a rear elevation view of the third embodiment of the body of FIG. 17;
FIG. 21 is a left side elevation view of the third embodiment of the body of FIG. 17;
FIG. 22 is a right side elevation view of the third embodiment of the body of FIG. 18;
FIG. 23 is a top plan view of the third embodiment of the body of FIG. 18;
FIG. 24 is a bottom plan view of the third embodiment of the body of FIG. 18;
FIG. 25 is a front perspective view of a fourth embodiment of a body of an electronic vaping device;
FIG. 26 is a rear perspective view of the fourth embodiment of the body of FIG. 25;
FIG. 27 is a front elevation view of the fourth embodiment of the body of FIG. 25;
FIG. 28 is a rear elevation view of the fourth embodiment of the body of FIG. 25;
FIG. 29 is a right side elevation view of the fourth embodiment of the body of FIG. 25;
FIG. 30 is a left side elevation view of the fourth embodiment of the body of FIG. 25;
FIG. 31 is a top plan view of the fourth embodiment of the body of FIG. 25; and,
FIG. 32 is a bottom plan view of the fourth embodiment of the body of FIG. 25.
The portions of the design shown in broken lines form no part of the claimed design.
